ELECTRONIC SWITCHING OF IGNITRON
TUBES FOR HEAVY LOADSStuart C. Rockafellow, Farmington, Mich., as
signor to Robotron Corporation

Application April 16, 1953, Serial No. 349,136

10 Claims. (Cl. 315—197)

1

This invention relates to an ignition system for ignitron tubes as used in resistance welding service and it more particularly relates to an electronic switching system for igniting alternate pairs of ignitron tubes, such alternate pairs being used to decrease the average load carried by each of said pairs.

In the designing of electric welding circuits utilizing ignitron tubes, it is well recognized that the current carrying capacity of such tubes is governed by what is termed a "duty cycle." For example, if a set of ignitrons carries 1000 amperes of current for 0.2 second in a 2 seconds on-off cycle, this would be referred to as a 10% duty cycle. If the same tubes were then caused to carry current for 0.4 second in a 2 seconds on-off cycle, this would constitute a 20% duty cycle and the safe tube rating, as established by the manufacturer would be materially less, as about 500 amperes of current.

On large loads, even the largest size of ignitrons commercially available are too small to carry the required loads at the cycles required and the amount of time that each set of ignitrons is conductive is reduced by using two sets of alternately energized ignitrons. In this manner, it becomes possible to handle substantially double the amperages which would otherwise be passed through a single set.

In previous attempts to utilize this pattern for connecting ignitrons in a welding circuit, reliance has been placed on mechanical relays to change the firing from one set of ignitrons to the other. However, the mechanical difficulties, particularly including the relatively short life, of such relays have seriously limited the usefulness of this type of circuit.

Accordingly, a major object of the invention is to provide a circuit for alternately firing two parallel connected sets of ignitrons without the necessity of using any mechanically moving parts.

A further object of the invention is to provide a circuit, as aforesaid, without the need for using relays.

A further object of the invention is to provide a circuit, as aforesaid, which is adaptable for use with phase shift control.

A further object of the invention is to provide a circuit, as aforesaid, in which a large number of different types of circuits may be used as the timing and controlling medium.

A further object of the invention is to provide a circuit, as aforesaid, in which the timing and controlling medium employs a conventional flip-flop circuit.

2

A further object of the invention is to provide a circuit, as aforesaid, which will be subject to close adjustment and which, when adjusted, will not readily get out of adjustment.

5 A further object of the invention is to provide a circuit, as aforesaid, which is capable of being built with sturdy apparatus and hence will have low maintenance requirements.

Other objects and purposes of the invention 10 will be apparent to persons acquainted with circuits of this general type upon a reading of the following description and an inspection of the accompanying drawings.

In the drawings:

15 Figure 1 constitutes a circuit diagram of apparatus embodying the invention.

Figure 2 constitutes a fragmentary circuit diagram of a modification.

In general, a thyatron firing circuit is provided for each of the ignitrons. The conductivity of the firing thyatrtons associated with one pair of ignitrons is controlled by a phase shift circuit including two switching thyatrtons as resistance elements therein. The conductivity of 25 the firing thyatrtons controlling the other pair of ignitrons is controlled by a second phase shift circuit similarly including two further switching thyatrtons as resistance elements therein. An electronic circuit, as a flip-flop circuit, provides a potential alternating between the grids of the 30 switching thyatrtons with respect to their respective cathodes, and thereby renders conductive alternate pairs of firing thyatrtons and of their associated sets of ignitrons.

35 Referring now to Figure 1 in detail, the source conductors 1 and 2 are connected to opposite terminals of any convenient source of alternating potential, as 110 volt, 60 cycle. The conductor 2 is connected through the primary winding 3 of the welding transformer 4 and thence through the parallel connected sets 6 and 7 of back-to-back connected ignitrons to the conductor 1. Each of said ignitrons 8, 9, 11 and 12 is provided with any convenient type of transformer 40 energized thyatron firing circuits. In the particular embodiment here used for illustrative purposes, the ignitron 8, for example, is connected by its anode to the anode of the firing thyatron 13 and by its starting electrode to the cathode of said firing thyatron. The grid of said thyatron is connected through the secondary winding 14 of a transformer 16 and through a source of constant bias potential 17, as a battery, to the cathode of said thyatron. Similar connections are made with respect to the firing thyra- 50

trons 18, 19 and 21 and the respectively connected secondary windings 22, 23 and 24 of the transformers 16 and 26.

All of the foregoing circuitry is conventional and will be so recognized by those skilled in the art.

Turning now to the control circuitry which is the particular subject matter of the present invention, the transformers 27 and 28 are connected by their primary windings 29 and 31 respectively in parallel with each other and between the source conductors 1 and 2. An initiating switch 32, which may be another electronic circuit, will normally be provided to initiate operation of the control circuit and thereby initiate conduction of the ignitrons.

Connected to the secondary winding 33 of the transformer 27 is a phase shift circuit 30 of any convenient type utilizing electric discharge devices as resistance elements thereof. In the circuit here shown, there is a capacitor 34 and a resistance circuit 36 connected in series with each other and with said secondary winding 33. The resistance circuit 36 includes the rectifiers 37 and 38 connected in opposite polarity with respect to each other and in series with each other and with the terminals 39 and 41 of said resistance circuit. A pair of switching thyatrons 42 and 43 are each connected by their anodes respectively to the terminals 39 and 41 and the cathodes of said switching thyatrons 42 and 43 are connected each to the conductor 44. A conductor 46 including a variable resistor 45 connects a point intermediate said two rectifiers with a point intermediate the cathodes of said two thyatrons 42 and 43. The output terminals 73 and 74 are connected to the primary winding 18 of the transformer 26.

The secondary winding 29 of the transformer 28 is connected to a similar phase shift circuit 35 including the capacitor 47 and the resistance circuit 48. Said resistance circuit 48 includes the switching thyatrons 49 and 51 which are connected into the phase shift circuit 35 and to the conductor 44 in the same manner as the switching thyatrons 42 and 43 are associated with the resistance circuit 36 and hence need no further detailing. The grids of the thyatrons 42 and 43 are connected together and connected to a conductor 52 and the grids of the thyatrons 49 and 51 are connected together and to the conductor 53. The output terminals 76 and 77 are connected to the primary winding 79 of the transformer 16.

Any convenient circuit 54 is provided for supplying a constant positive potential to the conductor 44 and a potential, which is negative with respect to the potential supplied to conductor 44, alternating between the conductor 52 and the conductor 53. In the particular embodiment here utilized to illustrate the invention, the circuit 54 comprises a conventional flip-flop circuit. The conductor 44 is connected to the positive side of a source 56 of constant potential, as a battery, and the negative side of said source is connected to the cathodes of a pair of thyatrons 57 and 58. The anodes of said last-named thyatrons are connected to the conductors 53 and 52. A capacitor 59 is connected between the anodes of said thyatrons 57 and 58. The conductor 44 is connected through a resistance 61 to the anode of the thyatron 57 and also by the conductor 62 through a variable resistance 63 and a capacitor 64 to the grid of the thyatron 58. Said last-named grid is also connected through a resistance

66 to the cathode of said thyatron 58. The conductor 44 is also connected through the resistance 67 to the anode of the thyatron 58 and is also connected by the conductor 68 through the variable resistor 69 and the capacitor 71 to the grid of the thyatron 57. Said last-named grid is also connected through a resistor 72 to the cathode of the thyatron 57.

The modification shown in Figure 2 illustrates a different type of circuit for resistance circuits 36 and 48. All of the parts of the circuit of Figure 2 which are identical with the parts of Figure 1 are designated by like numerals and need no further description. Further, said circuit connects to an ignitron circuit of the same nature as shown in Figure 1 and hence needs no further detailing. The resistance circuits utilized in this circuit are indicated at 36a and 48a and function with respect to the rest of the apparatus in the same manner as the circuits 36 and 48 of the circuit of Figure 1. The resistance circuits 36a and 48a themselves, however, are here shown as saturable reactors 83 and 84 having D. C. windings 85 and 86, respectively. With the D. C. windings deenergized, the resistance of the resistance circuits is high and a substantial phase shift is effected. With the D. C. windings energized, the resistance becomes negligible and the phase shift is at a minimum.

Operation

Considering first the "at rest" condition of the apparatus shown in Figure 1, namely, with the switch 32 open, the phase shift circuits will be deenergized and the constant bias in each of the grid circuits of the ignitron firing thyatrons 13, 18, 19 and 21 will hold said thyatrons non-conductive. Thus, the respectively connected ignitrons will be non-conductive.

With the closing of the switch 32, the transformers 27 and 28 will become energized and will place alternating potentials on the output terminals 73, 74, 76 and 77 of the phase shift circuits. Assuming now that there is no phase shift effected in the phase shift circuit 30, the primary winding 78 of the transformer 26 will be energized substantially in phase with the energization of the source conductors 1 and 2, thereby energizing the secondary windings 23 and 24 of said transformer. This will overcome the constant bias in the grid circuits of the thyatrons 19 and 21 and thereby cause same to become conductive which in turn will fire the ignitrons 8 and 9 substantially in phase with the potentials placed on their principal electrodes and they will conduct. Similarly, energizing of the phase shift circuit 35 will energize the primary winding 79 of the transformer 16 substantially in phase with the source conductors 1 and 2 and this in turn will overcome the constant bias in the grid circuits of the thyatrons 13 and 18. This will render said thyatrons conductive and fire the respectively connected ignitrons 3 and 9 substantially in phase with the potentials placed on their principal electrodes and they will conduct. Since the tubes 42, 43, 49 and 51 are of gas-filled type, there will be no gradual shift in phase output of the phase shift circuits but rather the phase shift circuits will produce output potentials of either fully phase shifted characteristics or substantially non-shifted characteristics insofar as the tubes 42 and 43 are concerned. However, if desired, the variable resistance 45, here shown as a single element but which may also be another electronic circuit, may be utilized to control the

minimum resistance in said resistance circuit 36 when said switching thyatrons are conductive and thus control the maximum heat produced at the welding electrodes.

The flip-flop circuit 54 will act in response to the negative potential applied by the battery 56 to produce alternate negative potentials on the conductors 52 and 53. Thus, the switching thyatrons 42 and 43 will be blocked at one given instant and the tubes 49 and 51 will be conductive. In this condition the phase shift circuit 30 will effect a maximum phase shift of the output of the transformer 26 with respect to the input thereof and this will fail to overcome the blocking potential applied to the firing thyatrons 19 and 21. Thus, the pair 7 of ignitrons will be non-conductive. At the same moment, with the switching thyatrons 49 and 51 conductive, the output of the phase shift circuit 35 will be substantially in phase with the input thereof and hence the secondary windings 14 and 22 will overcome the blocking bias otherwise applied to the thyatrons 13 and 18, said thyatrons will be conductive and the pair 6 of ignitrons will also be conductive.

As soon as the potential on the conductors 52 and 53 reverses with respect to the potential on the conductor 44, then the phase shift will appear in the phase shift circuit 35 and the pair 6 of ignitrons will be non-conductive. At the same time a minimum phase shift will appear in the phase shift circuit 30 and the pair 7 of ignitrons will be conductive.

The conduction of either pair of ignitrons will so diminish the potential between the junction points 81 and 82 as to preclude conduction by the other pair of ignitrons. Thus, after one phase shift circuit has fired one pair of ignitrons, a subsequent firing potential appearing from the other phase shift circuit on the other pair of ignitrons will have no effect. Accordingly, there is no possibility of overlapping of firing by the respective pairs of ignitrons. Further, each pair of ignitrons, when once started, will continue conducting until the anode potential falls below a minimum level. Thus, if the output of the flip-flop circuit 54 changes the potential applied to the phase shift circuits at a point of time intermediate the zero points of a given wave form applied to the conductors 1 and 2, conduction will continue in the pair of ignitrons then conducting until the potential between the conductors 1 and 2 returns substantially to zero and conduction will commence in the other pair promptly upon the reverse potential appearing between said conductors 1 and 2. Hence, there can be no overlapping of firing of respective pairs of ignitrons, nor can there be appreciable gaps between the firing of such respective pairs and the supply of welding current passed by said ignitrons will be of substantially uniform character.

It will thus be understood that as the output of each of said phase shift circuits 30 and 35 changes from a non-phase shifted to a phase shifted condition with respect to the phase of the input voltage on conductors 1 and 2, the respectively connected pairs of ignitrons will be rendered alternately conductive and non-conductive.

It will be recognized that the frequency of the output of the flip-flop circuit 54 will be adjustable by adjustment of the variable resistors 63 and 69 which for uniformity may, if desired,

be connected for simultaneous adjustment by a single control.

Thus, a circuit has been provided by which an entirely electronic means will render the pair 6 and the pair 7 of ignitrons alternately conductive and that the respective periods of conduction and non-conduction of each is readily controllable.

In the form of the invention shown in Figure 10 2, the saturable reactors 83 and 84 perform the switching functions of the switching thyatrons, 42, 43, 49 and 51 in response to the output of the circuit 54 in the manner above described. The remainder of the circuit functions in the same manner as above described in connection with the circuit of Figure 1.

While I have employed a specific embodiment for illustrating the invention, it will be recognized that many variations may be made from the specific circuit here shown, as will be recognized by those acquainted with the art, and that such variations will be included within the scope of the hereinafter appended claims, excepting as said claims may by their own terms expressly require otherwise.

I claim:

1. A circuit for firing two parallel connected pairs of back-to-back connected ignitrons in a load circuit, the combination comprising: first and second transformers each having two secondary windings; four circuits each including a firing thyatron connected one with each igniton for firing same and each including one of said secondary windings therein so connected that energization of said secondary windings will render conductive the firing thyatrons respectively connected thereto and thereby fire the igniton associated therewith, the two secondary windings so associated with one pair of ignitrons being of said first transformer and the two secondary windings so associated with the other pair of ignitrons being of the other transformer; first and second phase shift circuits, each including a resistance element therein, said resistance elements each including switching means becoming conductive or non-conductive in response to an independent potential applied thereto; conductors connecting the primary winding of each of said transformers with the output terminals of each respective phase shift circuit; a source of constant voltage, the positive side thereof supplying one side of said independent potential for each of said switching means and wholly electrical means connected to the negative side of said source and supplying the other side of said independent potential for alternately one and the other of each of said switching means.

2. A circuit for firing two parallel connected pairs of back-to-back connected ignitrons in a load circuit, the combination comprising: first and second transformers each having two secondary windings; four circuits each including a firing thyatron connected one with each igniton for firing same and each including one of said secondary windings therein so connected that energization of said secondary windings will render conductive the firing thyatrons respectively connected thereto and thereby fire the ignitrons associated therewith, and the two secondary windings so associated with one pair of ignitrons being of said first transformer and the two secondary windings so associated with the other pair of ignitrons being of the other transformer; first and second phase shift circuits,

each having a resistance component therein, said phase shift circuits each including a pair of switching thyratrons as said resistance component; a control conductor connecting the cathodes of said switching thyratrons; conductors connecting the primary winding of each of said transformers with the output terminals of each respective phase shift circuit; a source of constant voltage, the positive side thereof being connected to said control conductor and wholly electrical means connecting the negative side of said source alternately to one and the other of the grids of said switching thyratrons.

3. A circuit for firing two parallel connected pairs of back-to-back connected ignitrons in a load circuit, the combination comprising: first and second transformers each having two secondary windings; four circuits each including a thyatron connected one with each igniton for firing same and each including one of said secondary windings therein so connected that energization of said secondary windings will render conductive the thyratrons respectively connected thereto and thereby fire the igniton associated therewith, the two secondary windings so associated with one pair of ignitrons being of said first transformer and the two secondary windings so associated with the other pair of ignitrons being of the other transformer; first and second phase shift circuits, each having a resistance element therein and each of said phase shift circuits each including a pair of gas-filled electric discharge devices as said resistance element; a control conductor connecting the cathodes of said electric discharge devices; conductors connecting the primary winding of each of said transformers with the output terminals of each respective phase shift circuit; a source of constant voltage, the positive side thereof being connected to said control conductor and means including a flip-flop circuit connecting the negative side of said source alternately first to the grids of one pair of electric discharge devices and then to the grids of the other pair of electric discharge devices.

4. A circuit for firing two parallel connected pairs of back-to-back connected ignitrons in a load circuit, the combination comprising: first and second transformers each having two secondary windings; two circuits each respectively including a firing thyatron having its principal electrodes connected to the anode and starting electrode of each igniton and each firing thyatron having a secondary winding of one of said transformers and a source of constant bias potential in the grid-to-cathode circuit thereof; two further circuits each including a firing thyatron having its principal electrodes connected to the anode and starting electrode of the other igniton and each thyatron having a secondary winding of the other of said transformers and a source of constant bias potential in the grid-to-cathode circuit thereof; first and second phase shift circuits, each having a resistance component therein and each of said phase shift circuits each including at least one switching thyatron as said resistance component; a control conductor connecting the cathodes of said switching thyratrons; conductors connecting the primary winding of each of said transformers with the output terminals of each respective phase shift circuit; a source of constant voltage, the positive side thereof being connected to said control conductor and wholly electrical means connecting the negative side of said source alternately to one and the other of the grids of said switching thyratrons.

5. A circuit for firing two parallel connected pairs of back-to-back connected ignitrons in a load circuit, the combination comprising: first and second transformers each having two secondary windings; two circuits each respectively including a firing thyatron having its principal electrodes connected to the anode and starting electrode of each igniton and each firing thyatron having a secondary winding of one of said transformers and a source of constant bias potential in the grid-to-cathode circuit thereof; two further circuits each including a firing thyatron having its principal electrodes connected to the anode and starting electrode of the other igniton and each thyatron having a secondary winding of the other of said transformers and a source of constant bias potential in the grid-to-cathode circuit thereof; first and second phase shift circuits, each including a resistance element therein, said resistance elements each including switching means becoming conductive or non-conductive in response to an independent potential applied thereof; conductors connecting the primary winding of each of said transformers with the output terminals of each respective phase shift circuit; a source of constant voltage, the positive side thereof supplying one side of said independent potential for each of said switching means and wholly electrical means connected to the negative side of said source and supplying the other side of said independent potential for alternately one and the other of each of said switching means.

6. A circuit for firing two parallel connected pairs of back-to-back connected ignitrons in a load circuit, the combination comprising: first and second transformers each having two secondary windings; two circuits each respectively including a firing thyatron having its principal electrodes connected to the anode and starting electrode of each igniton and each firing thyatron having a secondary winding of one of said transformers and a source of constant bias potential in the grid-to-cathode circuit thereof; two further circuits each including a firing thyatron having its principal electrodes connected to the anode and starting electrode of the other igniton and each thyatron having a secondary winding of the other of said transformers and a source of constant bias potential in the grid-to-cathode circuit thereof; first and second phase shift circuits each having a resistance component therein, said phase shift circuits each including a pair of switching thyratrons as said resistance component; a control conductor connecting the cathodes of said switching thyratrons; conductors connecting the primary winding of each of said transformers with the output terminals of each respective phase shift circuit; a source of constant voltage, the positive side thereof being connected to said control conductor and wholly electrical means connecting the negative side of said source alternately to one and the other of the grids of said switching thyratrons.

7. A circuit for firing two parallel connected pairs of back-to-back connected ignitrons in a load circuit, the combination comprising: first and second transformers each having two secondary windings; two circuits each respectively including a firing thyatron having its principal electrodes connected to the anode and starting electrode of each igniton and each firing thy-

ratron having a secondary winding of one of said transformers and a source of constant bias potential in the grid-to-cathode circuit thereof; two further circuits each including a firing thyratron having its principal electrodes connected to the anode and starting electrode of the other ignitron and each thyratron having a secondary winding of the other of said transformers and a source of constant bias potential in the grid-to-cathode circuit thereof; first and second phase shift circuits each having a resistance element therein and each of said phase shift circuits each including a pair of gas-filled electric discharge devices as said resistance element; a control conductor connecting the cathodes of said electric discharge devices; conductors connecting the primary winding of each of said transformers with the output terminals of each respective phase shift circuit; a source of constant voltage, the positive side thereof being connected to said control conductor and means including a flip-flop circuit connecting the negative side of said source alternately first to the grids of one pair of electric discharge devices and then to the grids of the other pair of electric discharge devices.

8. A circuit for firing two parallel connected pairs of back-to-back connected ignitrons in a load circuit, the combination comprising: first and second transformers each having two secondary windings; four circuits each including a firing thyratron connected one with each ignitron for firing same and each including one of said secondary windings therein so connected that energization of said secondary windings will render conductive the firing thyratrons respectively connected thereto and thereby fire the ignitron associated therewith, the two secondary windings so associated with one pair of ignitrons being of said first transformer and the two secondary windings so associated with the other pair of ignitrons being of the other transformer; first and second phase shift circuits each having a resistance component therein and said phase shift circuits each including a pair of saturable reactors as said resistance components; a control conductor connecting one side of one of said saturable reactors to one side of the other of said saturable reactors; conductors connecting the primary winding of each of said transformers to the output terminals of each respective phase shift circuit; a source of constant voltage, one side thereof being connected to said control conductor and wholly electrical means connecting the other side of said source alternately to the other respective sides of one and the other of said saturable reactors.

9. A circuit for firing two parallel connected pairs of back-to-back connected ignitrons in a load circuit, the combination comprising: first and second transformers each having two second-

ary windings; two circuits each respectively including a firing thyratron having its principal electrodes connected to the anode and starting electrode of each ignitron and each firing thyratron having a secondary winding of one of said transformers and a source of constant bias potential in the grid-to-cathode circuit thereof; two further circuits each including a firing thyratron having its principal electrodes connected to the anode and starting electrode of the other ignitron and each thyratron having a secondary winding of the other of said transformers and a source of constant bias potential in the grid-to-cathode circuit thereof; first and second phase shift circuits each having a resistance component therein and said phase shift circuits each including a pair of saturable reactors as said resistance components; a control conductor connecting one side of one of said saturable reactors to one side of the other of said saturable reactors; conductors connecting the primary winding of each of said transformers to the output terminals of each respective phase shift circuit; a source of constant voltage, one side thereof being connected to said control conductor and wholly electrical means connecting the other side of said source alternately to the other respective sides of one and the other of said saturable reactors.

10. A circuit for rendering conductive two parallel connected pairs of back-to-back connected ignitrons in a load circuit, the combination comprising: first and second transformers each having two secondary windings; four circuits each including a firing electric discharge device connected one with each ignitron for firing same and each including one of said secondary windings therein so connected that energization of said secondary windings will alter the conductivity of the firing thyratrons in such a manner as to effect firing of the ignitron associated therewith, the two secondary windings so associated with one pair of ignitrons being of said first transformer and the two secondary windings so associated with the other pair of ignitrons being of the other transformer; first and second phase shift circuits each including a resistance element therein, said resistance elements each including switching means becoming conductive or non-conductive in response to an independent potential applied thereto; conductors connecting the primary winding of each of said transformers with the output terminals of each respective phase shift circuit; a source of constant voltage, one side thereof supplying one side of said independent potential for each of said switching means and wholly electrical means connected to the other side of said source and supplying the other side of said independent potential alternately to one and the other of each of said switching means.
